(57) **CLAIM**

The ornamental design for a bedstead, as shown and
described.

DESCRIPTION

FIG. 1 is a left front perspective view of a bedstead showing
my new design;

FIG. 2 is a front elevational view thereof;

FIG. 3 is a side elevational view of the headboard section,
the opposite side being a mirror image thereof;

FIG. 4 is a side elevational view of the footboard section, the
opposite side being a mirror image thereof;

FIG. 5 is a top view of the footboard section thereof;

FIG. 6 is a rear perspective view of the footboard section
thereof; and,

FIG. 7 is a front elevational view of the headboard section
thereof.

The views of the bedstead not shown form no part of the
claimed design. The dashed lines depicting ornamental
elements in headboard and bed rails represent environmental
elements only and form no part of the claimed design.
